Des. 208,087
Patented July 18, 1967

208,087

HOLDER FOR KNITTING NEEDLES AND ACCESSORIES

Clara S. Funk, Rte. 1, Box 191, Madras, Oreg. 97741

Filed Oct. 19, 1965, Ser. No. 87,584

Term of patent 14 years

(Cl. D3—19)

Fig. 1

Fig. 2

Fig. 3

FIG. 1 is a front elevational view of a holder for knitting needles and accessories showing my new design in closed position;

FIG. 2 is a side elevational view thereof;

FIG. 3 is a rear elevational view;

FIG. 4 is a front elevational view of the design shown in FIG. 1 in open position;

FIG. 5 is a side edge view thereof; and

FIG. 6 is a bottom edge view.

I claim:

The ornamental design for a holder for knitting needles and accessories, as shown.
